PANE SECURING MEANS

Ettore Bugatti, Molsheim, France

Application August 3, 1937, Serial No. 157,209
In France August 8, 1936

7 Claims. (Cl. 20—56.4)

In my U. S. Patent application Ser. No. 68,525, filed March 12, 1936, I have described a device for fixing window glasses, panels, and flat pieces of the same kind in a frame or support such as the recess of a window. The fixation device includes resilient means for backing the panel against flatwise pressure and a resilient panel retainer positioned in the recess of the support or frame in a transverse direction with respect to the panel, said retainer having its rear portion rigid with the frame or support and a freely flexible front portion provided with a beaded edge adapted to retain the panel in contact with the backing means; in an embodiment of the said device, the edges of the panel are inserted in an elastic sheath which is positioned between a projection or flange on the rabbet or like part of the frame or support, and a locking frame held in place by the panel retainer.

The object of the present invention is to provide changes and improvements in a device of this kind, especially with a view to facilitating removal of the panel or similar part from the frame or support.

According to an essential feature of the present invention, the retainer is attached to the locking or auxiliary frame, or even is wholly independent thereon, instead of being attached to the support or frame. When the retainer is made as a wholly independent element, it is resiliently distorted in order to be snapped into position and it is maintained in final position by reason of its own resiliency.

Furthermore, according to another feature of the present invention, I provide notches or recesses in the elements of the device so as to enable introducing a tool for bending or disengaging the retainer and thus facilitating withdrawal of the locking or auxiliary frame.

Other features of the present invention will result from the following detailed description of some specific embodiments thereof.

Preferred embodiments of the present invention will be hereinafter described, with reference to the accompanying drawing, given merely by way of example, and in which:

Fig. 1 is a sectional view of a glass pane portion fixed in a window frame by means of a device made according to an embodiment of the present invention, this section being made in a plane at right angles to the general plane of the glass pane, on the line I—I of Fig. 2;

Fig. 2 is a sectional view at right angles to the view of Fig. 1 and made along the broken line II—II of Fig. 1;

Figs. 3 and 4 are sectional views analogous to the sectional view of Fig. 1 and corresponding to two other embodiments of the invention, respectively;

Figs. 5 and 6 are sectional views, also analogous to Fig. 1, but corresponding to embodiments of the invention in which the retainers are wholly independent.

In the different figures of the appended drawing equivalent elements are designated by the same reference characters, respectively.

The glass pane 1 has its edges inserted in a marginal sheath or casing 2 of resilient material, rubber for instance, of U-shaped section, positioned in a housing provided in the recess 3 of the window. This sheath or case 2 is held between a wall of the housing and a locking or auxiliary frame 7 of L-shaped section. At spaced apart points, on the periphery on the outer side, frame 7 has projections or lugs 7' of rectangular section, which are formed to protrude by a predetermined amount on the auxiliary or locking frame. Lugs 7' are planed on their outer faces through which they are in contact with the wall 4 of the housing of the window recess which is at right angles to the wall against which sheath 2 is directly applied.

On the side of the frame that carries the lugs 7' there are fixed, for instance by means of rivets, elastic tongues 5, constituting the pane retainers. The hook-shaped free end 6 of the tongues engages a groove 4a provided in wall 4 as shown.

In view of the shape above described, the supporting lugs 7' hold the frame in an accurate position in the window recess and, owing to the provision of such lugs, the final trimming or finishing of the locking frame is expeditive since only a small number of narrow surfaces, viz the bearing surfaces of the lugs, has to be machined.

Rivets or like fastening means for attaching the retainer to the locking frame are preferably positioned where the lugs project from said frame as shown. By reason of the clearances between lugs 7', a tool such as a screw-driver may be inserted between the retainer 5 and the wall 4, for bending the retainer toward the frame and disengaging its hook from groove 4a, whereupon the auxiliary frame can be removed from the window recess.

In the embodiment of Fig. 3, instead of providing a recess 4a in the bottom of the housing, I provide relatively wide cavities or notches 4b in the front part of said housing, near the outer side of the window recess, and I dispose the retainers 5 in an inverse position as compared with that

they occupy in the embodiment of Fig. 1, each of said retainers bearing against a shoulder 4c provided on the edge of the corresponding notch. With this arrangement, it is easy to insert a hook-shaped tool behind the retainer so as to disengage it by pulling in the direction of arrow C.

I may also provide in the window structure inclined holes 11 which open behind the tongues and enable of pushing said tongues from behind, in the direction of arrow D, by means of any suitable tool or rod. Of course, in this case, the above mentioned notches are unnecessary.

On Fig. 4, I have shown another embodiment of the elastic retainer; the retainer is longer and is folded back at 5a then bent into a hooked edge adapted for engagement with a lip or abutment 4c projecting on the outer margin of groove 4b; in the example shown on Fig. 4, the locking frame 7 has a relatively less thickness, as compared to the depth of the window recess, than in the instance of Fig. 3. For removing the glass pane, it suffices to lift the retainer by means of any flat tool which is introduced into the folded portion 5a of the retainer, so as to disengage its hooked edge from the abutment 4c.

Figs. 5 and 6 show embodiments of the invention in which the retainers are no longer fixed to the window recess or the frame but are wholly independent and are held in position merely by their own elasticity which, so to speak, keeps them caught as a consequence of their shape.

In the embodiment of Fig. 5, the rear edge of the retainer is bent and forms a hook which engages a groove 12 provided in the bottom part of the housing of the window recess behind a heel or rib 13 provided in the lateral wall 4 of the window recess. The retainer, which is slightly curved or bent, bears at two points, on the one hand on heel 13, and on the other hand near the outer edge of wall 4. The front edge of said retainer is folded back at 5b over the body of said retainer itself and the end of this folded portion is slightly bent upwardly so as to come in front of the front face of the auxiliary or locking frame 7 and to hold it in position while compressing sheath 2 against the bottom of the housing of the window recess. The retainer is thus kept applied against heel 13 by the frame 7 itself. For removing the pane, it is only necessary to depress the retainer at 14 in the direction of arrow E so as to clear the auxiliary frame 7 from the holding edge of the retainer, whereupon the pane, sheath and auxiliary frame assembly may be withdrawn from the window recess.

The retainer shown on Fig. 6, which is based upon the same principle is slightly different. It is given the shape of a V, the apex of which is bent down so as to engage heel 13, as in the above described embodiment. The branches of the V bear, one against the side of the auxiliary frame 7, and the other (which is slightly curved) through its end against the edge 15 of the wall 4 of the window recess. The end 16 of the first mentioned branch is given the shape of a hook engaging the front face of the auxiliary frame.

In a general manner, while I have, in the above description, disclosed what I deem to be practical and efficient embodiments of the present invention, it should be well understood that I do not wish to be limited thereto as there might be changes made in the arrangement, disposition and form of the parts of the device without departing from the principle of the present in-

vention as comprehended within the scope of the appended claims.

In the claims, the word "pane" is used as a generic term to denote a flat element such as a glass pane, a panel of any kind and the like.

What I claim is:

1. In a holder for a pane, the combination of a stationary rear abutment for said pane, substantially parallel with the plane of the pane, having a front projection defining a back groove between the rear flange and said projection; a removable front abutment for said pane, also substantially parallel with the plane of the pane; and a resilient retainer substantially comprising three integral portions, a front portion attached to the movable front abutment, a but slightly bowed intermediate portion positioned in a plane substantially at right angles to the plane of the pane and a rear portion in the form of a hook removably engaging said groove, the retainer being adapted in operation to be stressed to tension between the front abutment and the groove.

2. In a holder for a pane, the combination of a main frame having a front recess defining a rear abutment for the pane, and a rear groove at the back part of said recess; a locking frame forming a front abutment for the pane dimensioned to be placed with marginal clearance in the recess, and having marginal projecting lugs constructed and arranged to fit snugly into the recess; and at least one resilient retainer, positioned in the recess along the marginal portion of the locking frame in a plane substantially at right angles to the pane, the retainer being attached to the locking frame solely through its front portion while the rear portion forms a freely deflectible flap having a back hook adapted to engage the said groove and the intermediate portion of said retainer being but slightly bowed and positioned in a plane substantially at right angles to the general plane of said frames.

3. A device for holding a pane along its margin, which comprises a first frame having the general shape of a box with a centrally apertured bottom and side walls, adapted to house the pane; a second frame having the general shape of a lid for the box, with a centrally apertured face and side walls; and at least one resilient retainer the intermediate portion of which is but slightly bowed positioned in operation between, and in substantially parallel relation with, adjacent overlapping side walls of the frames, the retainer having at one end releasable gripping contact with the corresponding lid wall in the vicinity of the apertured face of said lid and operatively engaging at the other end the first frame for retaining the frames against separation away from each other.

4. In a holder for a pane, the combination of a stationary rear abutment for said pane, substantially parallel with the plane of the pane, having a front projection defining a back groove between the rear flange and said projection; a removable front abutment for said pane, also substantially parallel with the plane of the pane; and a resilient retainer including oppositely bent hook-like edges and a but slightly bowed intermediate portion a part of which is adapted to lie flat on the side wall of said front abutment, said hook-like edges engaging respectively the groove and the edge of said front abutment.

5. In a holder for a pane, the combination of a stationary rear abutment for said pane, substantially parallel with the plane of the pane, having a front projection defining a back groove be-

tween the rear flange and said projection; a removable front abutment for said pane, also substantially parallel with the plane of the pane; and a resilient retainer V-shaped in cross section, the apex of the V being bent to form a hook and the end of a branch being oppositely bent to form another hook, said hooks engaging respectively the groove and the edge of said front abutment, and the other branch of the V freely diverging from the first branch.

6. A device for holding a pane along its margin, which comprises a first frame with a centrally apertured bottom and side walls providing a front inwardly projecting lip, adapted to house the pane; a second frame positioned in the apertured bottom, with a centrally apertured face and side walls; and a substantially flat resilient retainer disposed in a plane substantially at right angles to the plane of the pane, attached to the rear part of the second frame side wall and forwardly extending as a

free flap, said retainer being slightly bowed, in operation, in edgewise abutment against said lip.

7. In a structure of the type described, a main frame including an inwardly projecting rear flange and a second flange spaced apart from the former on the front side of the same, inwardly projecting by a minor amount; a pane having a resilient sheath disposed around its margin and retained thereon by a locking frame, an exposed portion of said sheath being located opposite the said rear flange on said main frame; and a substantially flat resilient pane retainer carried by said locking frame approximately at right angles to said pane and engaging said second flange on the main frame and exerting horizontal pressure thereon to press said sheath against said projecting rear flange for holding said locking frame and said pane firmly engaged to said main frame.
